GLASS HOLDER

Application filed September 29, 1930. Serial No. 484,975.

The present invention is a holder for drinking glasses and similar articles.

Important objects of the invention are to provide a holder of the type referred to, which will be of neat attractive design, of relatively simple and inexpensive construction and which may be readily set to securely hold drinking glasses of different sizes and shapes.

These objects are attained by the novel features of construction, combinations and relations of parts hereinafter described and broadly claimed.

The drawing accompanying and forming part of the specification illustrates one simple practical embodiment of the invention, but this illustration is intended primarily for disclosure, as the structure may vary within the true spirit and broad scope of the invention.

Fig. 1 is a plan view illustrating the device as hung from a bracket on the side of a table top and as partly open to receive the drinking glass; Fig. 2 is a side view partly in section; Fig. 3 is a bottom plan view of the device; Fig. 4 is a fragmentary detail view of portions of the base and holding levers.

As shown particularly in Fig. 1, there is provided in the present disclosure a base member 5, having an angularly upstanding hanger portion 6, projecting from one edge of the same and terminating at the upper end in a hook structure 7, adapted to be engaged over a supporting bracket 8 or the like, the latter in this instance being shown as attached by screws to the side of a table top 9. This hanger and base are shown as formed from a flat continuous strip of sheet metal and this is illustrated as ribbed at 10 in the angularly bent and vertically extending portions of the same to give it a desired degree of stiffness. The downwardly extending hook portion however, is left plain and flat so as to pass behind a bracket having only a slight projection, such as the bracket shown.

The drinking glass or other article 11 rests upon the base and is gripped or confined by surrounding holding devices here

shown as consisting primarily of the three upstanding rods or posts 12. These confining rods are shown as carried by the outer ends of the levers 13, which latter are confined beneath the base and pivoted by having their inner perforated ends 14 loosely engaged over the short bearing studs 15 projecting from the underface of the base. These pivot studs are indicated in Fig. 1 as secured to the base by being riveted thereto as at 16.

A disc 17 rotatably secured to the base by the central rivet 18 beneath the levers, holds the levers in position on their pivots, guides them in their in and out swinging movements and is utilized in the disclosure to actually swing them in and out and hold them in their various positions of adjustment.

As best shown in Fig. 3, the rotatable control disc 17 is formed with three arcuate cam slots 19 extending from the central toward the rim portion of the disc and receiving the short pins 20 on the underside of the levers. It will be evident in the view referred to that upon rotation of disc 17, the levers will be swung inward or outward, depending upon the direction of rotation and the holding rods carried by the levers be thereby closed in upon or opened away from a glass seated on the base. The incline of the cams is gradual enough to hold the levers in the various positions of adjustment and a further holding effect is present in the illustration by reason of the dishing of the disc as indicated at 21, which, as secured by the central rivet with its concave face upward causes it to yieldingly grip the outer portions of the levers after the manner of a spring washer. This spring holding construction prevents the disc from accidentally rotating or releasing the grip of the rods on the glass.

Additional holding means for the glass is provided in the illustration in the form of a lattice carried by the rods and consisting of flexible bent strips 22 pivotally connected at 23 in crossed relation and having their ends pivotally connected at 24 to form a continuous band, this band having attached by the pivots 24a, 24b, thimbles 25 and rings 100

or sleeves 26 at the upper and lower edges of the band and engaged over the rods to detachably mount the band in position. The thimbles at the upper end of the expandable and contractible band have a friction fit over the ends of the rods, so that the band will be properly retained in position, but the sleeves at the lower edge of the band have an easy sliding fit over the rods, so as not to offer too much opposition to desired adjustment of the holder.

If the lattice-work band is not required, the same may be readily slipped off the posts and the posts then be used entirely to confine or grip the glass. The lattice-work however, serves the extra purpose of a guard for the glass and also adds to the attractive appearance of the article.

What is claimed is:

20 1. A glass holder comprising a base, glass confining rods upstanding from said base, supports for said rods movably mounted on the base, a rotatable control disc mounted on the base and connected with said supports for shifting the same, said control disc being dished and frictionally gripping said supports.

25 2. A holder for a drinking glass or the like, comprising rodlike members mounted for movement toward or away from each other to fit different sizes and shapes of glasses and a contractible and expandable lattice work band having sleeve portions at the joints of the same removably engaged over said rodlike members and whereby said lattice work band may be readily applied to or removed from the rodlike members and when so applied, will contact or expand with said rodlike members for the adjustments 30 of the same to fit different glasses.

35 3. A holder for a drinking glass or the like, comprising a flat base provided with dependent pivot studs at the underside of the same, a control disc pivoted to the underside of the base, levers frictionally confined between said base and control disc, said levers being pivotally engaged at their inner ends over said pivot studs and the disc extending in supporting relation beneath 40 said levers to hold the latter thus confined on the pivot studs, pin and slot connections between the control disc and intermediate portions of the levers for swinging the levers with respect to the pivot studs at the inner 45 ends of the same and article holding members on the outer ends of the levers, said control disc being dished upwardly about the rim of the same to gain frictional engagement with the levers.

50 4. A holder for a drinking glass or the like, comprising a base for supporting the glass, said base having at one side of the same a laterally extended rigidly projecting supporting member by which the base may 55 be secured stationary to a suitable support,

70 a control disc pivoted to the underside of the base and having portions projecting laterally beyond the base and forming a handhold apart from the base convenient for turning the disc in relation to the base, levers pivoted on the base between the latter and the control disc and provided with upstanding article confining members, pin and slot connecting means between said pivoted levers and control disc whereby rotation of the latter will effect rocking movements on the levers on their pivots and said control disc and levers being relatively deformed out of a flat plane whereby the outer portions of the levers will be pressed upwardly by the outer portion of the disc and thereby frictionally held against the outer portion of the base.

75 80 85 In testimony whereof we affix our signatures.

LOUIS E. BALTZLEY.
